UNITED STATES PATENT OFFICE.

WILLIAM J. HUTCHINSON, OF CLARKSBURG, WEST VIRGINIA, ASSIGNOR OF
ONE-HALF TO JOHN REMLINGER, OF SAME PLACE.

FIRE-PLACE.

SPECIFICATION forming part of Letters Patent No. 366,630, dated July 12, 1887.

Application filed December 18, 1886. Serial No. 221,967. (No model.)

To all whom it may concern:

Be it known that I, WILLIAM J. HUTCHINSON, a citizen of the United States, residing at Clarksburg, in the county of Harrison and 5 State of West Virginia, have invented certain new and useful Improvements in Fire-Places; and I do hereby declare the following to be a full, clear, and exact description of the invention, such as will enable others skilled in the 10 art to which it appertains to make and use the same.

Figure 1 is a perspective view showing this device as a whole as when in use in a fire-place, but as now represented it stands on the 15 floor. Fig. 2 is a perspective view from the rear. Fig. 3 shows the several parts detached. Fig. 4 is a detail in cross-section showing how the space between the rear wall and end of the grate is partially filled.

20 This invention belongs to fire-places; and the novelty consists in the particular structure of each of the four parts, excepting the grate proper, which constitute the device, and each of which are made of cast-iron, and in their 25 combination, together with the grate, to form a complete fire-place, all as will now be set out and explained, reference being had to the accompanying drawings.

In the drawings, A denotes the side pieces, 30 the bottom and front edges, a a' , of which are at right angles to each other. The rear edge, a' , inclines rearwardly a little and makes an obtuse angle with the bottom edge. The top edge, a^2 , has an irregular line and extends from 35 the rear edge forwardly toward the front edge. Upon the inner face of each piece are the lugs a' , which are adapted, as usual, to hold the basket or grate E when the device is put together as in use. Toward the rear edge are the lugs 40 a^2 , placed near the bottom and centrally, and toward the top and on the extreme rear edge is the flange a^3 .

The back piece, B, is rectangular and extends from the back of the side pieces up to 45 the beginning of the irregular line a^3 . When the back is thus placed in position, it will incline from the bottom to the top, so as to leave a wider space at the top between it and the front than at the base, and thus the fire-chamber proper will be widest at the top.

To complete the covering of the back part of the fire-place, the piece C is provided. This in side elevation conforms in shape to the angular or irregular top lines, a^3 , of the side pieces. Underneath this piece C are flanges 55 c , two on each side, which leave the channel c' between them. When all the parts are put together, as in the complete fire-place, the top edges of the side pieces fit into the channels c' , made as above stated. The metallic bar D 60 is flat on the under side and oval on the top, and is designed to fit at the ends into the sockets a^3 in the side pieces.

The manner of using and applying the several pieces above described for the purpose of 65 making the fire-place is as follows: Into the sides of the fire-place or opening in the chimney-breast are placed the pieces A A. The ends of the bar D are now placed in their sockets in the side piece, and then the back is slid 70 into position between the lugs a^3 and the flange a^3 . The irregular-shaped piece C is now so placed upon the side pieces that the irregular top edges of the side pieces, A, fit into the 75 channels on the under side of this piece. Thus the side pieces are secured and held firmly together. The grate is now put in as usual, and fitted upon the lugs upon the inside of the side pieces. The rear end of the grate will 80 come within a short distance of the bar D, leaving a space for air and ashes between, while in like manner between the rear edge of the bar D and the back plate of the fire-place is another air and ash passage. When, now, the structure has been thus adapted and applied in its position in the fire-place, it will be 85 observed that by the peculiar structure of the irregular-shaped piece C a deflected surface is presented, which is especially adapted to radiate the heat in downward lines toward the 90 floor of the apartment. The upper part of this plate, at c^3 , inclines rearwardly, and, together with the formation of the chimney, constitutes the throat or smoke-escape.

While in above stating a method of putting 95 the several parts together for use, it will be perfectly obvious that the several parts can be united together outside of the opening in the chimney, and then the device as a whole can be set into the chimney. As a matter of com- 100

mon practice, I sell the several castings and the buyer can then set them up as he pleases when he wants to use them.

It will be observed that this device is very simple in structure and can be made very cheaply, while at the same time there is offered in the complete device, as placed in use in the chimney or fire-place, one that is not only exceedingly durable, but is an excellent heater. When in the course of use it is necessary to replace any parts, it is only necessary to purchase the proper member of the individual parts, and the worn-out or broken piece can be easily removed and the new piece 15 inserted in its place.

In setting the grate as ordinarily made it is frequently found that the bottom part does not extend sufficiently near to the back plate of the fire-place, so that not infrequently the space that is left between the rear edge of the grate and the back plate is too wide for practical purposes. The special office of the bar D is to partially fill up this space, so that in setting any ordinary grate 25 this space will be sufficiently filled for all practical uses. I am also enabled by this construction to have a deeper fire-place than can be otherwise had.

One exceedingly excellent feature in this 30 device is that there is not required any great skill in putting the parts together, so that any farmer or other householder who desires to have and use one of my fire-places can buy the several castings, and without the exercise of 35 any special skill can put them together in a completed form for use.

It is not necessary in preparing the several pieces for use to dress them up or to add any special preparation after they come out from 40 the molds. They come from the foundry in good shape for immediate use. When the parts are put together in the fire-place, there can be placed in front of them, about the edges, if desired, an ornamental front to afford a finish and make the outside appearance of the 45 grate very tasteful. For this front marble or

cast-iron can be used of any desired style of structure.

I am aware that outstanding stoves have been made of several pieces of casting, and 50 that these have been united together by various tie-rods, flanges, and in other ways. I am also aware that it is not new to have a curved top piece or arch in the rear of the fire-place for the purpose of more effectually radiating the heat into the room; but I am not aware that a device made and constructed as above described and for the uses set forth has ever before been known or used.

Having now described the objects, uses, and 60 advantages of my invention, what I claim as new, and desire to secure by Letters Patent, is—

1. A cast-iron fire place consisting of two side pieces, a back and top piece, the side 65 pieces having on their inner faces suitable lugs to receive the grate and near their rear edges lugs and flanges to hold the back plate, the top piece having on the under side and at the edges channels whereby it can be fitted upon 70 the edges of the side pieces, the several parts made and all combined in the manner and for the purposes set forth.

2. A cast-iron fire-place having side pieces, A, each having on the inside front and rear 75 lugs, as shown, and on the rear edge a flange, a', combined with the back piece, B, and the covering-piece C, having channels c' on each edge, substantially as described.

3. A cast-iron fire place consisting of the side 80 pieces, A, and back piece, B, these parts made as described and combined with the metallic bar D, situated between the rear end of the grate and the back plate of the fire-place, extending from side to side, substantially in the 85 manner and for the purposes set forth.

In testimony whereof I affix my signature in presence of two witnesses.

WILLIAM J. HUTCHINSON.
